UNITED STATES PATENT OFFICE.

GEORGE THOMPSON, OF VINCENNES, INDIANA.

DESIGN FOR A STOVE.

SPECIFICATION forming part of Design No. 34,724, dated July 2, 1901.

Application filed May 7, 1896. Serial No. 590,625. Term of patent 7 years.

To all whom it may concern:

Be it known that I, GEORGE THOMPSON, a citizen of the United States, and a resident of the city of Vincennes, in the county of Knox 5 and State of Indiana, have invented and produced a new and original Design for Stoves, of which the following is a specification, reference being had to the accompanying drawings, forming a part thereof.

The several features of my design will be apparent from the following description and claim.

In the accompanying drawings, in which similar letters of reference indicate corresponding parts, Figure 1 is a front elevation 5 of a stove embodying my design. Fig. 2 is a side elevation of the same. Fig. 3 is a rear elevation thereof.

For the purpose of illustrating my design I have shown it as applied to a heat-radiating stove.

I will now proceed to further describe my design in detail.

Upon the stove-base A (in the present instance containing the fire-box) the ornamentation consists of a series of scallop and scroll work of a beautiful design and so formed as to reflect the rays of light in a marked and attractive manner. This ornamentation extends substantially over the entire surface of the base. That part of the design which is at the corners A² of the base is carried down onto the leg A³ in continuous lines, thereby making the legs appear as one with the base 5 in the general design. The design of the front and of the drawer participates in the character of the design present on the corners of the base and legs, regard being had to the lines of the circular draft-door A⁵. The

design on said corners and front and legs is somewhat more massive and emphatic than the more delicate linework on the sides and rear A⁶ of the base. Above the base a handsome guard and foot iron B receives cross-markings B³, partaking somewhat of the appearance of claws, but conventional in pattern, and this claw-like ornamentation is carried up onto the supports B² of this guard 5

and is there modified with other minor elements of design.

The lower portion C of the cylindrical barrel of the stove has an open-work of a scroll and ogee pattern, as shown, of a graceful and attractive nature. Next above this design is a ring D, carrying another design. The outer 55 lower portion of this ring, especially at the sides and back thereof, carries a design intended to carry out and form continuations of certain of the upper curves and ornamentations of the part C of the stove. The front 60 part of this ring D is provided with a panel affording suitable space for any desired name. Above this is a continuation E of the stove-barrel, the rear portion E² of which is plain, with the exception of handsome bands E³. 65 The front portion E⁴ is handsomely decorated with scroll and curved-line work, in which regard is had for the handle E⁵, air or damper holes E⁶, and year-plate E⁷. A very attractive vertical beading E⁸ of curved and open 70 work bounds the side edges of the ornamentation of portion E⁴. This beading E⁸ has longitudinal rows of circular ornamental figures. At the upper end of the barrel occurs a top ring F, for the most part polished and 75 lustrous, but crossed at intervals by groups F² of lines, as shown. The upper side of the ring F has a concentric swelled part F³, carrying scrollwork and in turn surmounted by the open portion F⁴. On the top of the latter 80 stands the base of an urn G.

The various novel features of design heretofore enumerated combine to form a general design of an attractive, striking, and impressive character, having strong originality 85 and individuality.

What I claim as new and of my invention, and desire to secure by Letters Patent, is—

The design for a stove, substantially as shown and described.

Vincennes, Indiana, April 22, 1896.

GEO. THOMPSON.
